TYPEWRITING AND LIKE MACHINE

Russell G. Thompson, West Hartford, Conn., assignor to Remington Rand Inc., Buffalo, N. Y., a corporation of Delaware

Application August 29, 1939, Serial No. 292,461

8 Claims. (Cl. 197—74)

My invention relates to typewriting and like machines, and more particularly to improved case shift mechanism therefor.

The main object of my invention, generally stated, is to provide improved means of the character specified which is simple, reliable and highly effective in operation.

Another object of my invention is to provide improved case shift mechanism wherein the shiftable member may be easily shifted from one case position to the other and with greater certainty that the shiftable member is fully operated to each extreme shifted position.

Another object of my invention is to provide such case shift mechanism wherein the shiftable member in each extreme case shifted position is securely held against displacement due to rebound, jars, vibration and the like.

Another object of my invention is to provide resilient means in such case shift mechanism which acts on the shiftable member at each extreme case shifted position thereof to take up any looseness or play in the actuating connections and thereby insure definite shifted positions of the shiftable member and prevent vibration thereof in such positions.

Still another object of my invention is to provide cooperating adjusting means permitting accurate adjustment of each of the case shifted positions of the shiftable member as well as accurate adjustment of the holding means for the shiftable member to accord with the adjustment of the shifted positions thereof.

To the above and other ends which will hereinafter appear, my invention consists in the features of construction, arrangements of parts and combinations of devices set forth in the following description and particularly pointed out in the appended claims.

In the accompanying drawings, wherein like reference characters indicate corresponding parts of the different views:

Fig. 1 is a front, vertical, transverse sectional view taken through the central portion of a typewriting machine, and illustrating a sufficient number of parts thereof to show my invention in its embodiment therein.

Fig. 2 is a fragmentary, fore and aft, vertical sectional view taken on line 2—2 of Fig. 1 and viewed in the direction of the arrows at said line.

Fig. 3 is a fragmentary, detail sectional view showing certain parts of the case shift actuating means as they appear in a different case shifted position.

Fig. 4 is a fragmentary, horizontal, sectional

view of a detail of the case shift actuating means, the view being taken on line 4—4 of Fig. 2 and viewed in the direction of the arrows at said line.

I have shown my invention in the present instance embodied in a Remington Model No. 17 typewriting machine wherein a type basket is movable for case shifting. While the features of the present invention were designed primarily for embodiment in this machine and may be included therein without modifying or materially modifying the existing structural features thereof, it should be understood that the invention is not restricted to use in such machine but may be employed in a machine of the type having a platen or platen carrying carriage which is movable for case shifting. In other words, my invention may be applied to different types of machines wherein there is provided a relative case shifting movement between the type bars and platen, and when I refer herein to a "case shiftable part or member," I intend such term to have a generic meaning applicable to either a type basket, to a platen, or to any member which is arranged for case shifting movement.

The drawings show only so much of the construction of the Remington Model No. 17 machine as is necessary to arrive at an understanding of the present invention in its embodiment therein. The case shift mechanism is mounted within a frame comprising side plates 10 which are interconnected by cross members, one of which is a cross member 12 shown in part in Figs. 1 and 2. The case shiftable member in the present machine is a type basket which includes a type bar segment 14 of the usual construction carrying type bars 15 mounted in companion radial slots 16 and on a common fulcrum wire 17.

The type bars 15 are operated in the usual manner by suitable type actions including key levers and sub levers (not shown), each of which is connected to operate the companion type bar 15 through a pull link 18 as shown in Fig. 2. Each type bar 15 carries a lower case type 19 and an upper case type 20, and when the segment 14 is in its elevated position shown in Figs. 1 and 2, the lower case type 19 is moved to the printing point on a platen 21 with the aid of a type guide 22 in the usual manner. The type guide 22 is fixedly secured at 23 to the segment 14 which may be shifted downward from the normal position as will be hereinafter described to allow the upper case type 20 to be moved to the same printing point on the platen 21.

The upper portion of the segment 14 is guided on the cross member 12 for substantially vertical

case shift movement. Thus, left and right hand lateral extensions 24 and 25 on the segment are provided with ball race members 26 and 27 respectively which are fixedly secured thereto by headed screws 28. Each of the members 26 and 27 are grooved as shown in Fig. 2 to provide raceways for companion anti-friction bearing balls 30, which balls are also received in companion vertically disposed raceways formed by grooves in stationary race members 32 and 33 arranged opposite the race members 26 and 27 respectively. The stationary race members 32 and 33 are received in companion channels in opposite end portions of the cross member 12, and the position of each of the race members 32 and 33 in the companion channel is adjustably determined by associated fore and aft adjusting screws 35 and by associated lateral adjusting screws 36. In each instance the screws 35 and 36 are arranged above and below the center of the companion raceway. This arrangement permits each of the stationary race members 32 and 33 to be adjusted forward and rearward relative to the cross member 12 and also to or from the companion movable race members 26 and 27, and in each instance this adjustment is obtained both above and below the center of the companion raceway. By such adjustment absolute parallelism may be effected and maintained between each raceway in the members 32 and 33 and the associated raceways in the members 26 and 27. An accurate line of case shift movement of the segment 14 may therefore be afforded and yet the segment is firmly guided against any transverse displacement. In the present instance, the heads of the screws 28 are sufficiently long to prevent the bearing balls 30 from falling or riding out of their companion raceways.

Referring to Fig. 2 it will be seen that the extensions 24 and 25 of the segment 14 are provided with depending arm 38 and 39 respectively which are pivotally connected to companion arms 42 and 43 of a rock shaft 44. The pivotal connection between each of the depending segment arms and the companion rock shaft arm is formed by an associated shoulder screw 45 which is retained in the companion rock shaft arm by a nut 46. The rock shaft 44 is pivotally supported at its ends on shoulder pivot screws 48 received in tapped openings in the associated side plates 10 and retained in position by lock nuts 49 threaded thereon.

The segment 14 is thus guided for substantially vertical case shift movement, the bearing balls 30 guiding the upper portion thereof on the cross member 12, whereas the lower end of the segment is guided in its shifting movement by the pivotal connection thereof with the arms 42 and 43 of the rock shaft 44. It will be apparent that during such case shifting movement, the arcuate travel of the extreme lower end of the segment 14 about the axis of the rock shaft 44 will cause a very slight pivotal movement of the segment about the single bearing ball 30 at each side thereof.

The weight of the type basket including the segment 14 and parts carried thereby is counterbalanced by a contractile spring 54 connected to each of the arms 38 and 39 of the segment and extending upward to a companion bracket 55 secured at 56 to the associated side plate 10. The combined effective forces of the two springs 54 is sufficient to normally maintain the segment 14 and parts carried thereby in its elevated posi-

tion shown in Figs. 1 and 2, as will hereinafter more clearly appear.

The case shift movement of the segment 14 is controlled in the present instance by the usual manually operable key lever arrangement which is operatively connected to the segment by improved means which will hereinafter be described in detail. Thus, a rock shaft 60 is pivotally mounted, by means not shown, at each end on 5 the associated side plate 10, and a case shift key lever 62 is fixedly secured to each end portion of this rock shaft 60. Although only the left hand case shift key lever 62 is shown in the drawings, it will be understood that this key lever and the 10 parts carried thereby will be duplicated at the right hand end of the rock shaft 60. The central portion of each of the case shift key levers 62 is guided by a vertically disposed slot in a guide comb 63 which is secured at 64 to an inwardly extending ear on each of the side plates 10, and the forward end portion of the key lever 62 is provided with a case shift key 65.

Each of the case shift key levers 62 is provided with case shift locking devices which include a 15 shift lock lever 68 pivotally mounted thereon at 69 and provided with a key 70 at its forward end. A contractile spring 72 connects the lock lever 68 with the shift lever 62 and tends to normally maintain the lock lever in its upper position on 20 the shift lever shown in Fig. 2 where a laterally projecting lug 73 on the lock lever 68 engages the lower edge of the shift lever 62. A latching pawl 74 is pivotally mounted at 75 on the shift lever 62, and a spring 76 normally retains the 25 pawl 74 in its position shown in Fig. 2, where a rearward extension thereof engages the laterally projecting lug 73 of the lock lever 68.

A depression of the case shift lock key 70 initially causes a relative pivotal movement between the lock lever 68 and the shift lever 62 until a laterally projecting lug 77 on the locking lever 68 engages the upper edge of the shift lever 62. This initial relative movement between the levers 68 and 62 moves the lug 73 downward 40 to allow the pawl 74 to move under the force of the spring 76 to a position where the upper end thereof engages a plate 79 adjustably mounted by screws 80 on the guide comb 63. Continued downward movement of the key 70 moves levers 45 68 and 62 in unison through the lug 77 until the upper end of the pawl 74 is shifted by the spring 76 beneath the lower edge of the plate 79, so that when pressure on the lock key 70 is relieved, the pawl 74 is effective to hold the shift key 62 50 in its depressed position.

In order to release the case shift lever 62 from this locked position, a downward pressure may be exerted on the shift key 65 at either side of the 55 machine to relieve the frictional engagement of the end of the pawl 74 with the edge of the plate 79. This allows the spring 72 to move the pawl 74 to its released position through the lug 73 and thereby permits the shift lever 62 to return to its normal position when the pressure on the shift key 65 is released.

The means provided in accordance with the present invention for operatively connecting the case shift key lever mechanism with the segment 14 includes an upwardly extending arm 84 on the 60 left hand case shift key lever 62, which arm is provided with an opening at its upper end receiving the forward end of a pull link 85. An expansion spring 86 is provided on the pull rod 85 which engages a nut 87 threaded on the forward 70 end of the rod 85 and bears against the front

surface of the arm 84 to normally hold the arm in engagement with a second nut 88 also threaded on the rod 85. The rear end of the rod 85 is provided with a laterally extending portion entering a bearing hole at the central portion of an actuating arm 90 and is retained therein by a spring clip member 91 received in a groove at the end of the rod 85.

An eccentric bearing means is provided for adjustably mounting the actuating arm 90 for pivotal movement on the left hand side plate 10. Thus, a headed bearing member 94 enters a bearing opening at the upper end of the actuating arm 90, and a retaining screw 95 passes through an eccentric opening in this bearing member 94 and is threaded into a tapped opening in a spacing member 96 secured at 97 (see Fig. 1) to the left hand side plate 10. Thus, the bearing member 94 may be turned around the eccentrically disposed holding screw 95 to vary the pivotal axis of the actuating arm 90 relative to the associated side plate 10, and when the desired position of this pivotal axis is attained, the screw 95 may be tightened to securely clamp the bearing member 94 against said side plate.

The lower portion of the actuating arm 90 is provided with a bearing opening receiving the body portion of a headed pin 99 carried by a link 100, which link is in turn provided with a bearing opening receiving the body portion of a headed pin 101 carried by the upper end of a guide arm 102. The lower end of the guide arm 102 is adjustably mounted for pivotal movement on a bracket 103 by an eccentric bearing means comprising parts 104 and 105 which may be the same as parts 94 and 95 respectively which are employed to adjustably mount the actuating arm 90.

The bracket 103 is securely attached at 107 (Fig. 1) to the left hand side plate 10, and the headed bearing member 104 is received in a bearing opening in the guide arm 102 with the retaining screw 105 passing through an eccentrically disposed opening in said bearing member and threaded into the bracket 103. A link 109 is provided for connecting the segment 14 with the upper end of the guide arm 102, the upper end of this link being connected by a pivot screw 110 to a rearwardly extending bracket 111 fixedly secured at 112 (see Fig. 1) to the left hand depending arm 38 of the segment 14. The lower end of the link 109 is pivotally connected to the arm 102 and to the link 100 at the junction thereof by an opening in the link 109 which receives the body portion of the headed pin 101 so that the link 109 is disposed between the link 100 and the arm 102 as will be seen in Fig. 4. A contractile spring 115 extends between a rearwardly extending pin 116 on the cross member 12 on the machine frame and a rearward extension 117 of the actuating arm 90, and thus exerts a force on the actuating arm tending to return it to the position shown in Fig. 2.

An integral downwardly extending portion 120 is bent at right angles to the body portion of the actuating arm 90 to form an enlarged stop surface. At the normal position of the actuating arm 90 shown in Figs. 2 and 4, the rear face of the enlarged stop portion 120 engages a padded stop formed by a disc 122 of felt or any suitable resilient material, which disc is securely attached to a threaded holding member 123 received in a tapped opening in an angular lug 124 of the bracket 103.

This stationary resilient stop means 122-123 for the actuating arm 90 is adjusted by turning

the part 123 until the axis of the pivot pin 101 is disposed on a line between the axis of the pivot screw 110 and the axis of the adjustable bearing member 104. The adjustable bearing member 104 may then be turned about its eccentric retaining screw 105 until the correct elevated position of the segment 14 is obtained for writing lower case characters. In other words, the bearing member 104 is turned to raise or lower the type segment 14 through the guide arm 102 and link 109 in their straightened position until a position of the segment 14 is obtained wherein the lower case type 19 are "on their feet" at the printing position, or where the top and bottom portions of the lower case type produce a substantially even imprint. This adjusted position of the bearing member 104 may be retained by tightening the holding screw 105.

A slight lateral shift of the pivotal axis of the guide arm 102 may be caused by this adjustment of the bearing member 104, and accordingly the resilient stop means 122-123 may be given a slight further adjustment to again restore the alignment of the axes of the pivots 110, 101 and 104. After the final adjustment of the stop means 122-123 is attained, a nut 125 may be tightened on the threaded member 123 against the surface of the lug 124 to securely hold this position of adjustment.

The guide arm 102 and the link 109 thus constitute a toggle device which is straightened at the lower case position of the segment 14 and any force tending to displace the segment from this position acts directly against the dead center of the guide arm 102. The toggle device 102-109, however, may be easily operated from this straightened position by a manual depression of the shift key 65 at either side of the machine to effect a forward movement of the actuating arm 90 through the arm 84 and pull rod 85. This forward movement of the actuating arm 90 is stopped when it reaches the position shown in Fig. 3 by the engagement of the forward surface of the enlarged stop portion 120 with adjustable resilient stop means which may be similar to the stop means 122-123 previously described. Thus, a felt disc 128 is secured to a threaded holding member 129 threaded into a tapped opening in an angular lug 130 on the bracket 103.

It will be clear that the forward movement of the actuating arm 90 acts through the link 100 to cause the guide arm 102 to be moved forwardly around its bearing member 104, and the arm 102 acts through the link 109 to pull the segment 14 downward against the force of the springs 54. Thus, the segment 14 may be shifted downward against the force of the springs 54 by pressing the case shift key 65 at either side of the machine, and the segment may be retained in this shifted position by pressing either of the associated shift lock keys 70 to allow the latch pawl 74 to engage the lower edge of the lock plate 79 in the manner previously described. During this shift movement of the segment, the actuating arm 90 is operated to its position of arrest shown in Fig. 3 without compressing or materially compressing the spring 86 on the pull rod 85. In order to release the pawl 74, however, a downward pressure may be applied to the shift key 65 which is sufficient to slightly compress the spring 86. This disengages the upper end of the pawl 74 from the lower edge of the plate 79 which allows the spring 72 to operate the pawl 74 to its released position through the lug 73.

The forward position of arrest of the actuating

arm 90 is adjusted by turning the threaded member 129 in the lug 130 until the axis of the pivot 99 is disposed in a line between the axis of the bearing member 94 and the axis of the pivot 101. The lowered position of the segment 14 for writing upper case characters may then be adjusted by turning the bearing member 94 upon its eccentric holding screw 95 so that the upper case type 20 are "on their feet" at the printing position. In other words, the downward shifted position of the segment 14 may be adjusted by turning the bearing member 94 until the upper case type 20 print evenly at their upper and lower edges, and this adjusted position of the bearing member 94 may be retained by tightening its holding screw 95.

A slight lateral shift of the pivotal axis of the actuating arm 90 may be caused by the adjustment of the bearing member 94, and accordingly a slight further adjustment of the stop means 128—129 may be necessary to restore the alignment of the axes of the pivots 94, 99 and 101. The final adjusted position of the stop means 128—129 may be retained by tightening a nut 131 on the threaded member 129 to engage the surface of the lug 130.

The actuating arm 90 and the link 100 thus constitute a second toggle device which assumes a straightened position when the segment 14 reaches its lowered position for writing upper case characters, and any force tending to displace the segment from such position acts against the dead center of the actuating arm 90. The segment 14, however, as well as the case shift key lever mechanism and the actuating connections are returned from this lowered position shown in Fig. 3 to their normal elevated position shown in Fig. 2 by the force of the springs 54 which acts directly on the segment 14 and accordingly acts against the pivotal dead center of the actuating arm 90 in its position shown in Fig. 3. The provision of the spring 115, however, prevents the segment from being locked in its elevated position inasmuch as the spring 115 acts on the actuating arm 90 to move it out of its dead center position when the manual shifting force acting thereon through the pull rod 85 is relieved. After the arm 90 is thus moved from its dead center position, the springs 54 are effective to return the segment, key lever mechanism and associated parts to their normal elevated position shown in Fig. 2.

In accordance with the present invention, improved resilient means are provided for opposing the latter part of the movement of the segment 14 to each of its case shift positions. Thus, any looseness in the actuating connections is taken up by the movement of the segment to each of its case shifted positions against the force of said resilient means. The resilient means provided for this purpose in the present instance acts to oppose the latter part of the relative pivotal movement which occurs between the depending arm 39 of the segment 14 and the arm 43 of the rock shaft 44 during the case shift movements thereof.

Referring particularly to Figs. 2 and 3, it will be seen that the arm 43 extends at 135 beyond the pivotal connection thereof with the depending arm 39 of the segment 14. A flat leaf spring or resilient steel strip 136 is retained at its central portion by a screw 137 threaded into a tapped opening in the arm 43 above the pivot screw 45, and the spring strip 136 extends forward above the central portion of the arm 43 as well as rear-

ward over the arm extension 135. The rearward portion of the strip 136 is provided with side portions 136a which extend downward along the side edges of the arm extension 135 to prevent the strip from turning about the screw 137. The front and rear ends of the spring strip 136 are normally supported and biased upwardly by associated coiled expansion springs 140, the front spring being seated in a depression 141 in the 10 arm 43, while the rear spring is seated in a depression in the extension 135, as may be seen in Fig. 2. The springs 140 are sufficiently strong to normally hold the associated ends of the strip 136 upward out of engagement with the arm 43 and extension 135.

A rearward integral extension 144 is provided on the depending arm 39 of the segment 14, and a tapped opening in this extension 144 receives a contact screw 145. At the position of the parts 20 shown in Fig. 2, the contact screw 145 is adjusted in the extension 144 to engage the rearward portion of the spring strip 136 and to move it against the force of the associated coil spring 140 to a position where it either engages or nearly engages the upper surface of the arm extension 135. This adjusted position of the contact screw 145 may be retained by a nut 146 threaded thereon to bear against the upper surface of the extension 144.

30 A similar forward extension 149 on the depending arm 39 of the segment 14 is also provided with a tapped opening which receives a contact screw 150. When the segment 14 is shifted downward for writing upper case characters as 35 shown in Fig. 3, the contact screw 150 is adjusted to engage the forward portion of the spring strip 136 and to move it against the force of the associated coil spring 140 to a position where it either engages or nearly engages the upper surface of 40 the arm 43. Likewise this adjusted position of the contact screw 150 may be retained by tightening a nut 151 thereon to bear against the upper surface of the extension 149.

When the segment 14 is shifted downward from 45 its position shown in Fig. 2 to its position shown in Fig. 3, it will be clear that the contact screw 150 does not engage the associated end of the spring strip 136 until the segment nearly reaches its extreme lowered position, and accordingly no 50 resistance is offered by the associated coil spring 140 during the greater part of this case shift movement. However, as the actuating arm 90 and the link 100 approach their straightened relation shown in Fig. 3, the contact screw 150 55 engages the forward end of the spring strip 136 so that the straightening of the toggle device 90—100 moves the segment to its final position of arrest against the force of the associated coil spring 140. In this manner, the segment 14 is 60 retained in its lowered position under the tension of the forward spring 140 which takes up any looseness in the pivotal connections 110, 101, 99 and 94. This arrangement entirely prevents any possibility of vertical vibration of the segment while upper case characters are being written.

It will likewise be clear that during the return movement of the segment from its position shown 70 in Fig. 3 to its position shown in Fig. 2, the contact screw 145 does not engage the rearward portion of the strip 136 until the segment nearly reaches its extreme upper position, and accordingly no resistance is offered by the rearward coil spring 140 throughout the greater part of this return shift movement. However, as the link 109

and the arm 102 approach their straightened relation, the contact screw 145 engages the rearward portion of the strip 136 and the final movement of the segment 14 to its elevated position is effected against the force of the rearward coil spring 140 by the straightening of the toggle device 109-102. In this manner, the segment is retained in its elevated position under the tension of the rearward coil spring 140 which takes up any looseness in the pivotal connections 110, 101 and 104. Thus, any possibility of vertical vibration of the segment is also prevented while lower case characters are being written.

It will be seen that I have thus provided a simple and highly effective case shift mechanism wherein toggle devices are employed to hold the shiftable member in each case shift position against the tension of resilient means acting on the shiftable member to take up any looseness in the toggle connection which might afford vibration of the shiftable member. In this arrangement, it will be noted that the force of this resilient means acting on the shiftable member is directed against the pivotal dead center of one of the toggle devices at each case shift position so that the force of the resilient means does not tend to displace the shiftable member from either of its extreme shifted positions.

It will be noted moreover that the present case shift mechanism includes two toggle devices connected in series so that one toggle device straightens as the other toggle device breaks. This arrangement affords a very desirable operating characteristic inasmuch as the rapidly increasing mechanical advantage afforded by each of the toggle devices as it is moved toward its straightened position results in an appreciable decrease in the effort required to effect the final movement of the shiftable member to each extreme position. Thus, the maximum effort is required to move the shiftable member through the intermediate portion of its travel to provide greater certainty that the shiftable member reaches its extreme shifted position in each instance. It will also be clear that this arrangement permits the shiftable member to be retained in its shifted position by a minimum pressure on the case shift keys.

It will further be apparent that practically no noise is produced by the arrest of the shiftable member in either of the case shifted positions thereof, and the shiftable member cannot rebound from either of such shifted positions. This is due to the arrangement whereby the force incident to the arrest of the shiftable member is absorbed by the straightening of the toggle devices and any rebound force is directed against the pivotal dead center thereof. The provision of individual adjusting means for each of the toggle devices affords an accurate independent adjustment of each extreme case shifted position of the shiftable member, and the provision of padded adjustable stops for the actuating means affords a substantially noiseless arrest thereof at positions which may be adjusted to allow the associated toggle device to assume a straightened position, regardless of the adjustment of the shifted positions of the shiftable member.

Various changes may be made in the construction, and certain features therein may be omitted without departing from my invention as it is defined in the accompanying claims.

What I claim as new and desire to secure by Letters Patent is:

1. In a typewriting machine, the combination of a machine frame, a case shiftable member mounted for case shifting movement relative thereto, a guide arm pivotally mounted on said frame, a link connecting said arm with said case shiftable member and normally disposed in alignment with said guide arm, an actuating arm pivotally mounted on said frame, a second link connecting said actuating arm with said guide arm, spring means acting on said actuating arm to normally hold it out of alignment with said second link, key controlled means operatively connected with said actuating arm and arranged to cause movement thereof into alignment with said second link to simultaneously move said guide arm out of alignment with said first mentioned link and thereby shift said case shiftable member, resilient stops for limiting the movement of said actuating arm in each direction, and resilient means acting to supply tension to said case shiftable member at each extreme case position thereof.

2. In a typewriting machine, the combination of a case shiftable member mounted for shifting movements, a rock shaft operatively connected with said shiftable member for guiding the latter in its case shift movements, resilient means acting between said shiftable member and said rock shaft to oppose movement of the shiftable member to each extreme case shifted position, and actuating means for said shiftable member including a first pair of toggle elements operable when straightened to move said shiftable member to one extreme case shifted position against the force of said resilient means, and a second pair of toggle elements interconnected with said first pair of toggle elements and operable when straightened to move said shiftable member to the other extreme case shifted position against the force of said resilient means.

3. In a typewriting machine, the combination of a case shiftable member mounted for shifting movements, a rock shaft having arms pivotally connected to said shiftable member, resilient means acting between one of the arms of said rock shaft and said shiftable member to oppose the final movement only of said shiftable member to each extreme case shifted position, and actuating means for said shiftable member including a first pair of toggle elements operable when straightened to move said shiftable member to one extreme case shifted position against the force of said resilient means, and a second pair of toggle elements operatively connected to said first pair of toggle elements and operable when straightened to break the first pair of toggle elements and to move said shiftable member to the other extreme case shifted position against the force of said resilient means.

4. In a typewriting machine, the combination of a machine frame, a case shiftable member mounted for shifting movements in said frame, an arm pivoted on said frame and pivotally connected to said shiftable member, resilient means acting between said shiftable member and said arm for opposing relative pivotal movement between the shiftable member and the arm, and actuating means for said shiftable member including a first toggle device arranged when straightened to move the shiftable member to one extreme position against the force of said resilient means, and a second toggle device operatively connected to said first toggle device and arranged when straightened to break the first tog-

gle device and to move the shiftable member to the other extreme position against the force of said resilient means.

5. In a typewriting machine, the combination of a machine frame, a case shiftable member mounted for shifting movements in said frame, an arm pivoted on said frame and pivotally connected to said shiftable member, spring means carried by said arm at opposite sides of the pivotal connection thereof with said shiftable member, adjustable engaging means on said shiftable member coacting with said spring means to oppose movement of said shiftable member to either extreme case shifted position, and actuating means for said shiftable member including a first toggle device arranged when straightened to move the shiftable member to one extreme position against the force of said spring means, and a second toggle device operatively connected to said first toggle device and arranged when straightened to break the first toggle device and to move the shiftable member to the other extreme position against the force of said spring means.

6. In a typewriting machine, the combination of a machine frame, a case shiftable member mounted for shifting movement relative to said frame, spring means acting on said shiftable member to normally hold it in one case shift position, a first pair of toggle elements connected between said shiftable member and said frame and disposed in straightened relation when the shiftable member is in said case shift position, a second pair of toggle elements connected between said frame and the junction of said first pair of toggle elements, manual operating means connected to said second pair of toggle elements for straightening said second pair of toggle elements and breaking said first pair of toggle elements to

thereby shift said shiftable member to the other case shift position against the force of said spring means, and resilient means for breaking said second pair of toggle elements when the manual operating force thereon is removed to allow said spring means to return said shiftable member.

7. In a typewriting machine, a type bar segment mounted for substantially vertical case shift movement, a returning spring acting on said segment to normally hold it in an elevated position for writing lower case characters, a case shift key lever, and means operative by said key lever for shifting said segment to a lowered position for writing upper case characters, said means including a toggle device operative by said key lever to a straightened position to shift said segment against the force of said returning spring, spring means acting on said toggle device to move it from said straightened position, and resilient means acting to supply tension to said segment only at the extreme lowered position thereof.

8. In a typewriting machine, the combination of a machine frame, a case shiftable member mounted for shifting movement relative to said frame, a pair of toggle elements connected between said shiftable member and said frame and disposed in straightened relation when the shiftable member is in one case shift position, resilient means acting directly on said shiftable member to supply tension thereto only at the extreme case shift position thereof, and spring means acting on said toggle elements to normally hold the latter in straightened relation and thereby hold said shiftable member in said case shift position against the force of said resilient means.

RUSSELL G. THOMPSON.
